(57) **CLAIM**

The ornamental design for an electric liquid vaporizer bottle, as shown.

DESCRIPTION

FIG. 1 is a bottom perspective view of an electric liquid vaporizer bottle showing my new design;

FIG. 2 is a front view of the electric liquid vaporizer bottle of FIG. 1;

FIG. 3 is a rear view of the electric liquid vaporizer bottle of FIG. 1;

FIG. 4 is a right side elevational view of the electric liquid vaporizer bottle of FIG. 1;

FIG. 5 is a left side elevational view of the electric liquid vaporizer bottle of FIG. 1;

FIG. 6 is a top plan view of the electric liquid vaporizer bottle of FIG. 1; and,

FIG. 7 is a bottom plan view of the electric liquid vaporizer bottle of FIG. 1.

The broken line showing of environmental structure in FIGS. 1-6 is for illustrative purposes only and forms no part of the claimed design.
